GRILLE

Robert R. Candor, Dayton, Ohio, assignor to
General Motors Corporation, Dayton, Ohio, a
corporation of Delaware

Application September 28, 1935, Serial No. 42,648

4 Claims. (Cl. 98—114)

This invention relates to grilles and their manufacture, and more particularly to grilles which are to be used in connection with air conditioning or refrigerating apparatus.

5 An object of this invention is to provide an improved grille and an improved method of manufacturing a grille.

Further objects and advantages of the present invention will be apparent from the following 10 description, reference being had to the accompanying drawings, wherein a preferred form of the present invention is clearly shown.

In the drawings:

Fig. 1 is a plan view of one embodiment of my 15 grille;

Fig. 2 is a transverse cross-section of the grille in partly completed condition;

Fig. 3 is an enlargement of a portion of Fig. 1 with a portion of the frame broken away;

20 Fig. 4 is a perspective view of a portion of a sheet which may be used in the manufacture of a slightly modified form of the invention;

Fig. 5 is a view similar to Fig. 3, but showing a slightly modified form;

25 Fig. 6 is a cross-section of the strip shown in Fig. 4 taken midway between the grooves;

Fig. 7 is a view similar to Fig. 2, but showing a slightly modified form;

Fig. 8 is a view similar to Fig. 3, but showing 30 the form indicated in Fig. 7;

Fig. 9 is a view similar to Fig. 2, but showing a further modification;

Fig. 10 is a view similar to Fig. 3, but showing the modification indicated in Fig. 9;

35 Fig. 11 is a perspective of a portion of a grille using a further modified form; and

Fig. 12 is a diagrammatic representation of an air conditioning or refrigerating apparatus embodying my invention.

40 A grille embodying my invention includes, in general, a plurality of relatively thin metal sheets 10 and 11 stacked upon each other in such a manner that the main portions of the sheets are held in spaced parallel relationship.

45 The sheets may be held in spaced parallel relationship by means of a plurality of grooves 12 and 13. These grooves are formed on the sheets so that when the sheets are stacked together the grooves are in staggered relationship or in other differently disposed relationship as indicated in the drawings. The grille may be placed in a frame surrounding the periphery of the grille, which frame is preferably formed of an integral channel metal member 14 with its

flanges properly cut to form smooth corners, as at 15.

In the modification shown in Figs. 2 and 3 the grooves 12 and 13 are made at right angles to the length of the strips 10 and 11; but the grooves 12 on strips 10 are differently disposed with respect to the ends of the strip than are the grooves 13 with respect to the ends of the strips 11. In this manner two groups (a group of strips 10 and a group of strips 11) of strips are formed having grooves differently disposed with respect to their ends. Strips from alternate groups may be stacked upon each other so that the grooves of the strips of one group (10) rest against main portions of the strips of another group (11).

After the strips have been stacked, they may be secured together either by the frame 14, or by bonding the strips together, or both. The strips may be bonded together either by dipping them in the bonding material, such as molten solder, or they may be brazed in a reducing atmosphere, such as hydrogen, either by using strips of sheet metal, such as steel, coated with a small amount of bonding material such as copper or an alloy thereof; or the strips may be made of sheet metal, such as steel, and the bonding material may be sprinkled thereon in powdered form, being held in position by any suitable adhesive substance. Thus a grille may be formed comprising a plurality of relatively thin metal sheets stacked upon each other and having grooves arranged in staggered relation in which the sheets may be bonded together at the grooves.

Strip material may be used. Thus the sheets 10 and 11 may be formed from a single strip of material by passing said strip through a suitable groove-forming mechanism and thereafter the strips may be severed into a plurality of strips forming groups 10 and 11, or the group 10 may be formed from one strip of the material and the group 11 may be formed from a different 40 strip.

In the modifications shown in Figs. 4, 5 and 6, the strips 10a are similar to the strips 10, but one or both of the edges of the main portions of the strips are bent or deflected as indicated at 16. The strips 11a are similar to the strips 11, and likewise one or both edges are bent or deflected as indicated at 17. These deflections may extend gradually all the way between the grooves 12a, and all the way between the grooves 13a, or they may extend only for a portion of the distance between the grooves. The grille shown in Figs. 4, 5 and 6 may be formed and assembled in the same manner as the grille here- 55

tofore described with respect to Figs. 2 and 3, with the exception that the deflections 16 and 17 are added to the strips.

In the modification shown in Figs. 7 and 8, the construction is substantially the same as that shown in Figs. 2 and 3, with the exception that the grooves 12b of the strips 10b and grooves 13b of strips 11b are placed at an angle to the normal line of air-flow, which air-flow ordinarily is at a right angle to the length of the strip. The grooves 12b are in staggered relationship to the grooves 13b in a manner similar to that disclosed with respect to Figs. 2 and 3. The grille in this modification may be made in the same manner as that disclosed with respect to Figs. 2 and 3, with the exception that the grooves are formed at an angle to the normal of the length of the strip.

In the modification shown in Figs. 9 and 10, the grooves 12c of the strips 10c are at an angle to the normal air-flow, and the grooves 13c of the strips 11c are at a differently directed angle to the normal air-flow. The angle of the grooves 12c may be the same in number of degrees as the angle of the grooves 13c, but in a different direction. However, it is to be understood that the angle of the grooves 12c may be a different number of degrees than the angle of the grooves 13c; and in fact, the angles of the grooves 12c may also differ among themselves as well as differ from the angles of the grooves 13c, which, in turn, may also differ from each other in angularity. The grille shown in Figs. 9 and 10 may be manufactured substantially the same as described with respect to the grille of Figs. 2 and 3, with the exception that the angle of the grooves is changed.

The modification shown in Fig. 11 is somewhat similar to that shown in Figs. 9 and 10; but the grooves 12e of the strips 10e are perpendicular to the length of the strip, whereas the grooves 13e of the strips 11e are at an angle to the normal air-flow. It is understood that the grille structure shown in Fig. 11 may be manufactured in a manner similar to that described with respect to Figs. 2 and 3 and may be placed in a frame substantially in the same manner.

The groove structures and the deflections 16 and 17 are particularly useful in insuring proper air-flow through the grille when the grille is used in air conditioning or refrigerating apparatus. The air flowing through the grille is acted upon by the grooves and deflectors to diffuse the same and prevent objectionable drafts on the occupants of the room.

When used for air conditioning, the strips of material may be made of any suitable size. For example the strips may be between one-half and three-quarters of an inch in width and other dimensions may follow the proportions of the drawings. This is by way of example, however, and may be varied as desired.

Fig. 12 shows diagrammatically an air conditioning apparatus using my grille. Fig. 12 may be taken to be either a horizontal or a vertical cross-section of the apparatus. The apparatus may include an air tempering or cooling coil 20 through which air flows and is conditioned by either being refrigerated, dehumidified or heated and/or humidified. The air is caused to flow through the structure by means of a fan 21

driven by a motor 22. The air then flows through the grille structure 23, which may be any of the embodiments previously described, and is discharged into the enclosure. The grille not only modifies and diffuses the air passing therethrough, but hides any unsightly structures within the air conditioning apparatus. The coil 20 may be connected to a source of heating or cooling fluid. Thus it may be connected to a refrigerant liquefying unit 24 including a motor 10 25 which drives a compressor 26. The compressor may be connected to a condenser 27 and receiver 28. The receiver 28 may be connected through an automatic expansion valve 29 with the coil 20. The coil 20 may be connected by the 15 suction line 30 with the compressor 26. A thermostat or a humidostat 31 governs the operation of the motor 25 in accordance with air conditions created by or effecting the air conditioning apparatus. The coil 20, or a similar coil, may be 20 connected to a furnace for heating, if desired.

While the form of embodiment of the invention as herein disclosed, constitutes a preferred form, it is to be understood that other forms might be adopted, all coming within the scope of 25 the claims which follow.

What is claimed is as follows:

1. A grille comprising a plurality of metal strips each having relatively long substantially straight portions separated by relatively narrow cross grooves integrally formed therein, said grooves projecting in the same general direction, the grooves of each strip being staggered relative to the grooves of the strip immediately adjacent thereto whereby the bottom portions of the 35 grooves in one strip engage the straight portions of the adjacent strip.

2. A grille composed of a plurality of metal strips each having similar transversely disposed narrow channels separated by relatively long straight portions, the channels of each strip being staggered relative to the channels of the adjacent strips, said strips being so arranged that the channels of each strip serve to space said strip from the adjacent strip and all of said 40 channels being disposed with the open side facing in the same direction.

3. A grille comprising a plurality of metal strips each having relatively long substantially straight portions separated by relatively narrow cross 50 grooves integrally formed therein, said grooves projecting in the same general direction, the grooves of each strip being staggered relative to the grooves of the strip immediately adjacent thereto whereby the bottom portions of the 55 grooves in one strip engage the straight portions of the adjacent strip, and a frame member holding said strips in assembled relationship.

4. A grille comprising a plurality of metal strips each having relatively long substantially straight portions separated by relatively narrow cross 60 grooves integrally formed therein, said grooves projecting in the same general direction, the grooves of each strip being staggered relative to the grooves of the strip immediately adjacent 65 thereto whereby the bottom portions of the grooves in one strip engage the straight portions of the adjacent strip, said strips comprising means for diffusing the air flowing through the grille.

ROBERT R. CANDOR.
